CLAIM

The ornamental design for a transaction card enclosure, as shown and described.

DESCRIPTION

FIG. 1 is a front perspective view of a transaction card enclosure shown in an unfolded planar condition;

FIG. 2 is a front elevation view of the transaction card enclosure of FIG. 1;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof;

FIG. 8 is a rear perspective view of a transaction card enclosure shown in a folded condition;

FIG. 9 is a front perspective view of the transaction card enclosure of FIG. 8;

FIG. 10 is a front elevation view thereof;

FIG. 11 is a rear elevation view thereof;

FIG. 12 is a right elevation view thereof;

FIG. 13 is a left elevation view thereof;

FIG. 14 is a top plan view thereof; and,

FIG. 15 is a bottom plan view thereof.

Included in the claim are the long evenly spaced broken lines (---) at the top quarter of the card in FIGS. 1 through 3, 9, and 10 depicting a single straight perforation, and the long dash-dot broken lines (- - - -) depicting horizontal fold lines at the right and left sides of the card and the top edge of each of the three larger rectangles in FIGS. 1 through 3, 9 and 10. All other broken lines depict environmental subject matter and form no part of the claimed design.
